UNITED STATES PATENT OFFICE

2,613,296

TRIP-FREE CIRCUIT BREAKER

Morris B. Wood, Newburyport, Mass.

Application June 24, 1949, Serial No. 101,013

14 Claims. (Cl. 200—116)

1

The present invention relates to electrical circuit breakers, particularly of the trip free type and is herein illustrated as embodied in a compact and easily assembled form which automatically resets itself in readiness for reclosing after having opened its circuit upon the occurrence of overload conditions.

An object of the invention is to provide a trip free overload circuit breaker of improved construction and form capable of being constructed inexpensively and of operating reliably and with good durability under a wide range of operating conditions. Another object is to provide a circuit breaker of the trip free type which will reset itself automatically for reclosing and which may then be reclosed and reopened repeatedly under overload conditions. A still further object is to provide a circuit breaker of the type referred to with a simply actuated, manual operating connection and at the same time to provide a quick closing or opening action, thus improving the durability of the contacts.

To the accomplishment of the above noted objects the circuit breaker of the present invention comprises the usual contacts, a pair of cam members, one of which actuates the contacts and a thermostatic latch engaging the other cam member to lock it in fixed position, in which a wedging device in the form of concentric rolls is provided acting on the contact actuating cam member to close the contacts against the resistance offered by the locked cam member. By this arrangement it is possible to provide the locked cam member with a projection for retaining the wedging device in either of two positions, with the contacts closed or opened. The projection may accordingly be constructed to insure a quick closing or opening action for the contacts. This feature of the invention also contemplates the provision of resilient members for forcing the wedging device out from between the cam members when the locked cam member is released so that a separate resetting movement to relock that cam member is unnecessary.

These and other features and advantages of the invention, as hereinafter described and claimed, will be apparent to those skilled in the art from the following detailed specification, taken in connection with the accompanying drawings, in which:

Fig. 1 is sectional view of a trip free electrical circuit breaker embodying the features of the present invention, showing the parts thereof in positions assumed with the circuit through the breaker closed;

2

Fig. 2 is a similar view of the parts in positions assumed with the circuit opened:

Fig. 3 is a similar view of the operating parts of the breaker shown in positions assumed at an intermediate condition, directly after opening the circuit as a result of excessive current flow, but before the contact actuating wedging device has been forced out from between the cam members;

Fig. 4 is a perspective detail view on a somewhat enlarged scale of the contact actuating cam member;

Fig. 5 is a similar view of the latch engaging cam member;

Fig. 6 is a similar view of the wedging rolls; and

Fig. 7 is plan view of the wedging rolls showing their manner of contact with the two cam members.

The circuit breaker illustrated in the drawings is of the trip free type, so called, because of the arrangement of parts, with which it is impossible to hold the contacts closed under conditions of excessive current flow in the circuit controlled by the breaker. The circuit breaker is manually operated and tripped to open the contacts by the action of a current responsive latch, the action of which is to lock the contacts closed or to release them for quick opening upon excessive current flow.

The illustrated circuit breaker comprises a hollow rectangular frame or casing 10 of insulating material, having one end open, with mounting flanges or lugs projecting beyond the contour of the frame at the sides. All of the operating parts are inserted through the open end of the frame and are easily assembled within the frame in operating relation. After assembly in the frame the open end thereof is closed by a cover or face plate 12.

The operating parts of the circuit breaker include contacts 14 and 16, and a swinging contact actuating member 18 composed of relatively wide resilient metallic strip material bent to surround a supporting pivot pin 20 at its central portion and curved to form a cam along one arm disposed at an angle to the other arm which carries the contact 14. To actuate the member 18 it is acted upon by a manually actuated wedging device in the form of a set of three concentric rolls 22, 24 and 26, acting against the resistance offered by a second swinging cam member 28 of rigid construction having a yoke portion straddling the contact actuating cam member 18 at the end portions of the pivot pin 20. The pivot pin passes through slots 21 in the yoke portion

of the member 28 and the sides of the yoke portion are bent toward each other with one side flanged outwardly to provide a relatively narrow central cam arm on the member 28. Near the juncture of the flanged out cam arm of the member 28 an abrupt shoulder 30 is formed engaging the current responsive thermostatic latch, indicated at 32, of bimetallic material formed with a right angle toed out free end. When the latch 32 engages the shoulder 30 the member 28 is locked and the contacts may be closed or opened by forcing the wedging rolls between or out from the cam members.

To force the wedging rolls between or out from the cam members the rolls are mounted on a pin 34 the ends of which are secured in a pair of parallel links 36. The upper ends of the links 36 are pivotally connected to a manually actuated plunger 38 slidably mounted in a sleeve portion of the cover 12. When the plunger is depressed the contacts are closed as in Fig. 1. When the plunger is pulled outwardly the contacts are opened as in Fig. 2.

To enable the wedging rolls to be moved easily between the cam members 18 and 28 the two outer rolls 22 and 24 are formed with a larger diameter than the inside center roll 26. The outside rolls bear individually on the relatively wide surface of the cam member 18. The central cam arm of the member 28 being relatively narrow enters between the rolls 22 and 24 and engages the center roll 26 (see Fig. 7). As the wedging rolls move between the cam members they turn in opposite directions, thus reducing the frictional resistance to that of the rolls on the pin 34, since each roll engages one only of the cam members.

The cam members are yieldingly pressed together so that the wedging rolls will be retained in a definite relation with the cam members or released therefrom, and the cam arm of the member 28 has a projection 39 (see Fig. 5) for this purpose, as well as, to provide a quick closing and opening action for the contacts. For yieldingly pressing the cam members together each cam member is connected with its own resilient means in the form of springs 40 and 42, respectively. The spring 40 is connected to the member 18 and causes the contacts to be opened when the rolls are ineffective to hold them closed. The spring 42 is connected to the cam member 28 and is weaker than the spring 40, so that when the thermostatic latch 32 releases the cam member 28 the resistance offered by the spring 42 will be overcome by the spring 40 and the contacts will be opened. The cam member 28 will then be forced into an intermediate position, shown in Fig. 3. As soon as the intermediate position is reached the projection on the cam member 28 engages the roll 26 below the pin 34 urging it outwardly and releasing it from between the cam members, projecting the connected plunger also outwardly. As the plunger moves outwardly the cam member 28 follows the movements of the roll 26 until the roll reaches the position of Fig. 2. When this position of the roll is reached the cam member will be returned to its relocked position with relation to the latch 32. The breaker will then be ready for a new reclosing operation merely by depressing again the plunger 38.

To prevent the cam member 18 from moving too far with the rolls 22 and 24 when the latch engaging cam member 28 no longer offers resistance to keep the contacts closed, the wedging

rolls are guided in their movements and the plunger 38 is mounted to reciprocate between a pair of inwardly projecting ribs 44 on frame 10 and the cam member 18 has a pair of laterally projecting tabs 46. The tabs 46 are so arranged that they engage the ribs 44 when the contacts are opened. The ribs therefore limit the opening movement of the contacts.

The thermostatic latch 32 provided with the toed out free end is arranged to move beneath the shoulder 30 on the cam member 28 when in unheated condition. It is heated by direct passage of current therethrough and when heated to a predetermined temperature it releases the cam member 28 to open the contacts. The latch is mounted for easy adjustment to enable convenient calibration of the circuit breaker for different overload current values in a manner similar to the latching strip disclosed in United States Letters Patent No. 2,418,537 granted April 8, 1947 upon application of the present inventor. For this purpose the frame 10 has a groove 48 running inside its right hand wall and the latch is secured to a terminal plate 50 secured to the inside of the frame by a screw 52 passing through the side wall of the frame. The end of the latch 32 which is secured to the terminal plate 50 is bent in a direction reverse to the main portion of the latch and is disposed within the groove 48. Just below the point where the latch is secured to the terminal plate the plate has a threaded opening to receive an adjusting screw 54 passing loosely through the wall of the frame. Between the adjusting screw 54 and the securing screw 52 the terminal plate 50 is weakened by a perforation 56 to facilitate flexure of the strip resulting from rotation of the adjusting screw 54. The perforation 56 also receives the lower end of the latch 32 when releasing the cam member 28.

The circuit through the breaker runs from the terminal plate 50, the latch 32, a flexible jumper 58 running through an opening in the cam member 18 to a point of attachment with the cam member directly above the contact 14, the contact 14, contact 16, and a terminal plate 60 secured to the bottom of the frame by a screw 62. The use of the flexible jumper enables the current to pass through the circuit breaker without flowing through the operating parts to any considerable extent.

To enable the cam member 28 to be released from the latch 32 and then to slide freely along the right angle end of the latch without frictional binding, the cam member 28 is shiftable on the pivot pin 20 within the length of the slot 21. This arrangement enables the cam member 28 to relatch itself freely also after having been released from the latch, without movement of the latch. After the shoulder 30 on the cam member 28 is raised above the right angle end of the latch it slides along the pivot pin 20 to locked position.

With the construction described the circuit breaker can not be held manually closed and it will reset itself as soon as the rolls are forced out from between the cam members. All that is then necessary to do is to depress again the plunger 38 and the circuit will be reclosed. If the conditions causing excess current flow have not been corrected however the circuit will immediately be reopened. In resetting the breaker the plunger 38 to which the rolls are connected is forced manually through the sleeve portion of the cover, indicating the opening of the breaker.

The nature and scope of the invention having been indicated and an embodiment of the invention having been described, what is claimed is:

1. A trip free circuit breaker having contacts, a pair of cam members, one of which actuates the contacts, a thermostatic latch engaging the other cam member to lock it in fixed position and resilient means for actuating the cam members, in combination with a wedging device in the form of concentrically mounted rolls acting on said contact actuating cam member for closing the contacts against the resistance offered by the locked cam member and said resilient means, each of said concentric rolls engaging one only of the cam members.

2. A trip free circuit breaker having contacts, a pair of swinging cam members having a common pivot, one of which cam members actuates the contacts, a manually operated wedging device for swinging the cam members away from each other about said pivot and resilient means for actuating the cam members together, in combination with a thermostatic latch for locking the other of said cam members in position to cause the contacts to be closed by the wedging device against the resistance offered by the locked cam member and the resilient means.

3. A trip free circuit breaker having contacts, a pair of swinging cam members having a common pivot, one of which cam members actuates the contacts, a manually actuated wedging device for swinging the cam members away from each other about said pivot and resilient means for actuating the contact actuating cam into circuit opening position, in combination with a thermostatic latch engaging the other cam member to lock it in position where the contacts may be closed by the wedging device against the resistance offered by the locked cam member, said latch engaging cam member having a projection to retain the wedging device between the cam members but to release the wedging device from between the cam members when the latch engaging cam member is unlocked and is swung to one side, and second resilient means for urging the wedging device out from between the cam members when released by the projection and for urging the latch engaging cam member into relocked position.

4. A trip free circuit breaker having contacts, a pair of cam members, one of which actuates the contacts, a thermostatic latch engaging the other cam member to lock it in fixed position and resilient means for actuating the cam members together, in combination with a wedging device acting on said contact actuating member for closing the contacts against the resistance offered by the locked cam member and said resilient means, one of the cam members having a surface of extended width, engaging the wedging device and the other cam member having a relatively narrow surface engaging the wedging device and the wedging device comprising three concentric rolls, two of which are spaced apart and act on the cam member of extended width and the remaining one of which acts on the cam member having the narrow surface.

5. A trip free circuit breaker having contacts, a pair of cam members, one of which actuates the contacts, a thermostatic latch engaging the other cam member to lock it in fixed position and resilient means for actuating the cam members together, in combination with a wedging device acting between the cam members for closing the contacts against the resistance offered by the

locked cam member and said resilient means, one of the cam members having a surface of extended width engaging the wedging device and the other cam member having a relatively narrow surface engaging the wedging device and the wedging device comprising three concentric rolls, the two outside ones of which act on the cam member of extended width and the inside one of which is smaller in diameter than the outside ones and acts on the narrow cam member while rotating in a direction opposite to that of the outside rolls.

6. A trip free circuit breaker having contacts, a pair of cam members, one of which actuates the contacts, a thermostatic latch engaging the other cam member to lock it in a fixed position and resilient means for actuating the cam members together, in combination with a wedging device acting between the cam members for closing the contacts against the resistance offered by the locked cam member and the resilient means, the contact actuating cam member having a surface of extended width engaging the wedging device, the locked cam member having a relatively narrow surface engaging the wedging device and the wedging device comprising three concentric rolls, the two outside ones of which act on the contact actuating cam member and the inside one of which acts on the locked cam member while rotating in a direction opposite to that of the outside rolls.

7. A trip free circuit breaker having contacts, a pair of cam members, one of which actuates the contacts, a thermostatic latch engaging the other cam member to lock it in fixed position and resilient means for actuating the cam members together, in combination with a wedging device acting between the cam members for closing the contacts against the resistance offered by the locked cam member and the resilient means, the contact actuating cam member having a surface of extended width engaging the wedging device, the locked cam member having a relatively narrow surface engaging the wedging device and the wedging device comprising three concentric rolls, the two outer ones of which are of larger diameter than the inside one, a manually actuated plunger for actuating the wedging device and a link connecting the wedging device with the plunger.

8. A trip free circuit breaker having contacts, a pair of cam members, one of which actuates the contacts, a thermostatic latch engaging the other cam member to lock it in a fixed position, a frame formed with inwardly projecting guiding ribs and resilient means for actuating the cam members together, in combination with a wedging device acting between the cam members and being guided between the ribs and a plunger mounted for reciprocation between said ribs, one of the cam members having laterally projecting tabs arranged to engage the edges of said ribs to limit the movement of the tab bearing cam member toward the other cam member under the action of the resilient means when the wedging device is moved from between them.

9. A trip free circuit breaker having contacts, a pair of cam members, one of which actuates the contacts, a pivot about which both cam members swing, a thermostatic latch engaging the other cam member to lock it in fixed position and resilient means for actuating the cam members together, in combination with a wedging device acting between the cam members for closing the contacts against the resistance offered by the locked cam member and the resilient means, the

contact actuating cam member itself also being composed of resilient material and the locked cam member being relatively rigid.

10. A trip free circuit breaker having contacts, a pair of cam members, one of which actuates the contacts, a thermostatic latch engaging the other cam member to lock it in fixed position and resilient means for actuating the cam members together, in combination with a set of wedging rolls acting between the cam members for closing the contacts against the resistance offered by the locked cam member and the resilient means, the contact actuating cam member itself also being composed of relatively wide resilient material against which two of the rolls act and the locked cam member being composed of relatively narrow rigid material against which acts one of the rolls disposed between the others.

11. A trip free circuit breaker having contacts, a pair of cam members, one of which actuates the contacts, a thermostatic latch engaging the other cam member to lock it in fixed position and resilient means for actuating the cam members together, in combination with a set of concentric wedging rolls acting between the cam members for closing the contacts against the resistance offered by the locked cam member and the resilient means, the contact actuating cam member itself being composed of relatively wide material against which two of the rolls act and the locked cam member being in the form of a yoke with a central projecting cam arm against the edge of which acts a third one of the rolls disposed between the said two rolls acting on the contact actuating cam member.

12. A trip free circuit breaker having contacts, a pair of cam members, one of which actuates the contacts, a thermostatic latch engaging the other cam member to lock it in fixed position and resilient means for actuating the cam members together, in combination with a set of concentric wedging rolls acting between the cam members for closing the contacts against the resistance offered by the locked cam member and the resilient means, the locked cam member having a slot and fulcrum pivot pin mounting aligned with the thermostatic latch to enable relatching without movement of the latch.

13. A trip free circuit breaker having contacts, a pair of swinging cam members having a com-

mon pivot, one of which cam members actuates the contacts and a manually actuated wedging device for swinging the cam members away from each other about said pivot, in combination with a current responsive latch engaging the other cam member to lock it in position where the contacts may be closed by the wedging device against the resistance offered by the locked cam member, said latch engaging cam member having a projection to retain the wedging device between the cam members but to release the wedging device when the latch engaging cam member is unlocked and is swung to one side, resilient means for urging the wedging device out from between the cam members when released by the projection and other resilient means for returning the latch engaging cam member to locked position.

14. A trip free circuit breaker having contacts, a pair of swinging cam members having a common pivot, one of which cam members actuates the contacts and a manually actuated wedging device for swinging the cam members away from each other about said pivot, in combination with a current responsive latch engaging the other cam member to lock it in position where the contacts may be closed against the resistance offered by the locked cam member, said latch engaging cam member having a projection to retain the wedging device between the cam members but to release the wedging device when the latch engaging cam member is unlocked and is swung to one side, and two springs, one of which is connected to the contact actuating cam member to open the contacts and the other of which is connected to the latch engaging cam member to press the wedging device out from between the cam members after the contacts are opened and to turn the latch engaging cam member to locked position after releasing the wedging device.
